UNITED STATES PATENT OFFICE.

SMITH SMITH, OF MARCUS HOOK, PENNSYLVANIA.

WATER-HEATING SYSTEM FOR DWELLINGS, HOTELS, AND THE LIKE.

1,135,410.

Specification of Letters Patent. Patented Apr. 13, 1915.

Application filed May 29, 1914. Serial No. 841,859.

To all whom it may concern:

Be it known that I, SMITH SMITH, a subject of the King of England, residing at Marcus Hook, in the county of Delaware and State of Pennsylvania, have invented certain new and useful Improvements in Water-Heating Systems for Dwellings, Hotels, and the like, of which the following is a specification.

10 The present invention relates to improvements in water heating systems for dwellings, hotels and the like.

The objects of this invention are:

First, the provision of a system such as 15 described which will render the supply of hot water throughout a dwelling more constant and which will safeguard the boiler against bursting and render introduction of cold water into the said boiler noiseless.

20 Second, to facilitate the turning off of the water supply, and emptying of the boiler in case of leaks, and to permit of the elimination of what is commonly termed the "dip pipe" and to furnish an exhaust pipe direct 25 from the boiler or tank to the reservoir through which cold water is supplied to the boiler, safeguarding against bursting of the water pipes and preventing the siphoning of water from the boiler, when the water supply is cut off from the mains.

25 Third, the provision of a system designed to prevent hot water from passing back through the meter in the event that one is employed, when the water is cut off in the street. This insures against the hot water carrying particles of rubber from the various 35 appliances and also particles of rust from the boiler back through the meter, which would have a tendency to clog the latter and 40 prevent its successful operation.

With the above and other objects in view, the present invention consists in the combination and arrangement of parts herein-after more fully described, illustrated in the 45 accompanying drawings and particularly pointed out in the appended claims, it being understood that various changes may be made in the form proportion, size and minor details without departing from the spirit or 50 sacrificing any of the advantages of the invention.

In the drawings:—Figure 1 is a vertical sectional view taken through a portion of a building showing my improved water heat-

ing system applied; and Fig. 2 is a detailed 55 sectional view of the reservoir illustrating a modified form of exhaust pipe.

Referring to the accompanying drawing by similar characters of reference through the several views, the numeral 5 designates 60 generally a fragment of a conventional form of building showing the first floor 6, second floor 7, third floor 8 and cellar 9, it being understood, however, that this construction of building is only used for the purpose of 65 illustrating the application of my invention and that the system may be arranged entirely upon one floor of a building or in any other manner desired. On the first floor of the building is a kitchen 10 in which is 70 located a sink 11 and water-back range 12 of any desired construction, the same being shown in the drawings merely in a conventional form.

The numeral 13 designates a boiler located on the second floor 7, while supported above the same and preferably located on the third floor 8 is a supply tank, or reservoir 14 to which cold water is supplied through the pipes 15 which are connected 75 to the water main 16, the supply of water from said main to the pipes 15 being controlled by a stop cock 17.

A branch pipe 18 leads from the cold water supply pipe 15 into the reservoir 14 85 and is controlled by a valve 19 actuated through the medium of the float 20 to retain the water in said reservoir at the same level. This reservoir 14 is preferably closed, being provided however, with a vent pipe 21 and 90 overflow pipe 22 located above the normal level of the water therein as shown in Fig. 1 of the drawings. The pipes 15 are provided with the customary cold water faucet 23 ar- 95 ranged convenient to the sink 11, while a hot water faucet 24 is also located adjacent this cold water faucet and also convenient to the said sink 11 and is in communication with the upper end of the tank 13 through the hot water supply pipes 25 and branch 100 pipe 26 which is connected to said hot water supply pipe 25 by the T-coupling 27. An exhaust pipe 28 is also connected to this T-coupling 27 and is preferably equipped with a goose-neck 29 extending through an 105 opening formed in the top of the reservoir 14 and having its lower end above the level of the water contained in said reservoir, as

illustrated in Fig. 1 of the drawing. A feed pipe 29' extends from the bottom of the reservoir 14 to a branch pipe 30, which is connected to the lower end of the tank 13. 5 This feed pipe 29' and branch pipe 30 constitute a means for conducting water from the reservoir 14 to said tank 13. The flow of water in the pipe 29' is controlled by a valve 31 by means of which the supply of water 10 to the tank or boiler 13 can be regulated when the valve 33 is closed.

A drain pipe 32 connects the branch pipe 30 with the hot water supply pipe 25 and is controlled by a valve 33 for a purpose to be 15 later explained.

The boiler or tank 13 is connected to the hot water back of the range 12 through the pipes 34 and 35 arranged to permit of a free circulation of hot water through the boiler 20 or tank 13 and water back of the said range 12.

As shown in Fig. 2 of the drawings which illustrates a slight modification in the form of exhaust pipe 28, the exhaust pipe 28^a is 25 connected to the coupling 27 in a similar manner as the exhaust pipe 28. In this form of invention the goose-neck 29 is dispensed with and a vertical extension 28^b projects upwardly from the bottom of the reservoir 30 14 above the level of the water therein, at which point the said extension 28^b is provided with an inverted bell shaped nozzle 29^b through which steam or the like is discharged against the inner walls of the reservoir 14 where it condenses and runs back 35 into the reservoir.

If for any reason it is desired to remove all the hot water from the boiler or tank 13, the valve 31 is first closed which prevents 40 entrance of any more cold water into the said boiler or tank 13 except that which is in the pipes 29' and 30. The valve 33 and faucet 24 are opened which permits the contents of the boiler 13 to drain out through 45 the branch pipe 30, drain pipe 32 and the hot water supply pipe 25 into the sink 11 or into any desired receptacle placed therein.

If it is desired to drain the cold water from the reservoir 14, also, the valve 36 50 is closed while the valves 31 and 33 are opened which permits water from the said reservoir to flow out through the pipes 29', 32 and 25 respectively into the sink or an equivalent receptacle. It will be noted that 55 this operation has no effect upon the draining of the hot water back of the range 12 or the water in the circulating pipes 34 and 35 which obviously retains at all times a certain amount of water in the water back 60 of the range 12 thereby preventing bursting of the water back or pipes. It will also be noted that the supply of cold water is admitted into the tank 13 at the lower end thereof which causes this cold water to mingle 65 with the hot water contained within

the tank or boiler 13, obviously making said admission of water into the tank or boiler noiseless.

From the foregoing description taken in connection with the accompanying drawings, it will be manifest that a water heating system is provided for hotels, dwellings and the like which will fulfil all the necessary requirements of such an apparatus. 70

What is claimed is:—

1. In a system such as described, a boiler, a feed pipe leading into the lower portion of said boiler, a hot water supply pipe leading from said boiler and discharging below the same, a discharge pipe leading from said hot water supply pipe and a valve controlled communication between said feed pipe and hot water pipe for draining said boiler. 80

2. In a system such as described, a boiler, a reservoir, means for supplying water to said reservoir, a feed pipe connecting said reservoir and the lower portion of the boiler, a hot water supply pipe leading from said boiler and discharging below the same, a valve controlled connection between said hot water supply pipe and feed pipe, and an exhaust pipe leading from the hot water supply pipe into said reservoir. 85

3. In a system such as described, a boiler, a reservoir, a feed pipe for supplying cold water to said reservoir, means for feeding cold water from said reservoir into said boiler at the lower end thereof, means for heating water within said boiler, a hot water pipe leading from the boiler and discharging below the same, a valve controlled connection between said hot water pipe and feed pipe, an exhaust pipe leading from the hot water pipe, and valves for controlling the passage of water to the reservoir and between said reservoir and boiler. 95 100

4. In a system such as described, a boiler, a reservoir mounted above said boiler, a cold water supply pipe leading to said reservoir, means for automatically controlling the supply of water to the reservoir from said cold water supply pipe, a feed pipe connecting the reservoir with the lower portion of the boiler, a hot water supply pipe leading from the top of the boiler and discharging below the same, an exhaust pipe connecting the said hot water pipe with said reservoir, and a valve controlled communication between said hot water pipe and the feed pipe. 110 115

5. The combination in a system such as described with hot and cold water fixtures, and a range hot water back, of a boiler, a reservoir located above said boiler, a cold water supply pipe leading to the reservoir and in communication with the cold water faucet, a valve in communication with the cold water supply pipe for controlling the supply of cold water to the reservoir, said valve being interposed between said reservoir and cold water faucet, means for auto- 120 125 130

matically controlling the supply of water to the reservoir from said cold water supply pipe, a feed pipe leading from the reservoir into the bottom of said boiler, a valve controlling the passage of water through said feed pipe, circulating pipes connecting the boiler with the range water back, a hot water supply pipe leading from the boiler and discharging below the same, said hot water faucet being connected to the hot water supply pipe, an exhaust pipe leading from the

hot water supply pipe into the reservoir, a drain pipe connecting the hot water supply pipe with the feed pipe, and a valve controlling the passage of water through said drain pipe.

In testimony whereof I have affixed my signature in presence of two witnesses.

SMITH SMITH.
